CLAIM

The ornamental design for an inflatable infant vehicle seat/bed, as shown and described.

DESCRIPTION

FIG. 1 is a side elevational view of an inflatable infant vehicle seat/bed, showing my new design;
FIG. 2 is a top plan view thereof;
FIG. 3 is a bottom plan view thereof;
FIG. 4 is a front elevational view thereof;
FIG. 5 is a rear elevational view thereof; and,
FIG. 6 is a top, front, side isometric view thereof.
The broken lines in FIGS. 1-5 are for environmental purposes only and form no part of the claimed design.

FIG. 1

FIG. 2
